FIG. 5 is a top view thereof;

FIG. 6 is a bottom view thereof;

FIG. 7 is an enlarged view of a portion 7 of FIG. 1;

FIG. 8 is an enlarged view of a portion 8 of FIG. 2;

FIG. 9 is an enlarged rear view of the portion 8 of FIG. 2;

FIG. 10 is an enlarged top view of the portion 8 of FIG. 2;

FIG. 11 is a cross sectional view taken along the line 11-11 of FIG. 8;

FIG. 12 is a cross sectional view taken along the line 12-12 of FIG. 8;

FIG. 13 is a cross sectional view taken along the line 13-13 of FIG. 8;

FIG. 14 is a cross sectional view taken along the line 14-14 of FIG. 8;

FIG. 15 is a cross sectional view taken along the line 15-15 of FIG. 8;

FIG. 16 is a top, front, right perspective view of a tapered roller bearing cage according to a second embodiment showing our new design;

FIG. 17 is a front view thereof;

FIG. 18 is a rear view thereof;

FIG. 19 is a right side view thereof, the left side being a mirror image;

FIG. 20 is a top view thereof;

FIG. 21 is a bottom view thereof;

FIG. 22 is an enlarged view of a portion 22 of FIG. 16;

FIG. 23 is an enlarged view of a portion 23 of FIG. 17;

FIG. 24 is an enlarged rear view of the portion 23 of FIG. 17;

FIG. 25 is an enlarged top view of the portion 23 of FIG. 17;

FIG. 26 is a cross sectional view taken along the line 26-26 of FIG. 23;

FIG. 27 is a cross sectional view taken along the line 27-27 of FIG. 23;

FIG. 28 is a cross sectional view taken along the line 28-28 of FIG. 23;

FIG. 29 is a cross sectional view taken along the line 29-29 of FIG. 23;

FIG. 30 is a cross sectional view taken along the line 30-30 of FIG. 23;

FIG. 31 is a top, front, right perspective view of a tapered roller bearing cage according to a third embodiment showing our new design;

FIG. 32 is a front view thereof;

FIG. 33 is a rear view thereof;

FIG. 34 is a right side view thereof, the left side being a mirror image;

FIG. 35 is a top view thereof;

FIG. 36 is a bottom view thereof;
